UNITED STATES PATENT OFFICE.

JOHN A. BARNES, OF DALLAS, TEXAS, ASSIGNOR TO FOWLER COMPANY, INCORPORATED, OF DALLAS, TEXAS, A CORPORATION.

BLOW-OUT BOOT.

Application filed June 16, 1925. Serial No. 37,488.

To all whom it may concern:

Be it known that I, JOHN A. BARNES, a citizen of the United States of America, residing at Dallas, in the county of Dallas and State of Texas, have invented certain new and useful Improvements in Blow-Out Boots, of which the following is a specification, reference being had therein to the accompanying drawing.

10 My invention relates to blow-out boots such as are used within pneumatic automobile and truck tires of the ordinary, low pressure or balloon type, to strengthen and reinforce the tire at a point where it has become weakened, due to a blow-out, break, rim cut, or hole therein, and has particular reference to an improved edge reinforcement for the staple, eyelet, or other fastening means usually employed to hold the 15 longitudinal edges of the boot in attached position to maintain the boot in fixed position about the inner tube.

20 In various forms of blow-out boots now appearing on the market, the fastening means employed to hold the boot in fixed position about the inner tube beneath the hole, rim cut, break or blow-out in the tire casing, comprises a plurality of mating staples or loops provided with inwardly 25 projecting, penetrating prongs, which enter the material of the boot immediately adjacent the opposite longitudinal edges thereof. These staples or loops are arranged in staggered relation on opposite longitudinal edges 30 of the boot, and are positioned to extend outwardly beyond the said edges, and, when the edges are brought together about the inner tube, the series of loops will coact to form a closed passageway for a thong or 35 other strip adapted to fasten the edges of the boot together. In the use of such forms of blow-out boots, the boot is fastened about the deflated inner tube, and the thong or strip passed through the coacting loops 40 formed by the staples. The tube and boot are then positioned within the tire casing with the boot beneath the hole, cut, or other weakened section of the casing: the tire and tube are placed in position on the rim; and 45 the tube inflated to the proper degree of pressure. During such inflation, the fabric or cord material of which the tire casing is made expands from 3 to 5 per cent, and it is at once apparent that the blow-out boot 50 positioned within the casing will be sub-

jected to a like expansion. Since the fabric or cord material of which the boot is made up is relatively heavy, it is apparent that there will be an enormous pull on the fastening loops or staples employed to normally maintain the boot in position about the inner tube, which pull is often sufficient to rip the penetrating prongs through the edge fabric of the boot and thus destroy or render ineffective the loop or staple fastening means. This tendency of the prongs to fray out, unravel, or pull through the edge of the boot, while readily noticeable in boots constructed of knitted or woven fabric, is especially noticeable in boots made of cord 60 fabrics, which material consists of superimposed layers of diagonally arranged cords coated and held together with rubber. Such cord fabrics constitute the ideal material for making blow-out boots for use within the 65 commonly-used cord tires, of the ordinary, low pressure or balloon types, but because of the diagonal arrangement of the cords, and the elastic nature of the rubber employed to bind the material together, the 70 said cord material does not possess the necessary holding strength or power along its longitudinal edges, and the penetrating 75 prongs, eyelets, or other fastening means soon pull through or unravel the edges of 80 the material and thus render the fastening means ineffective. In blow-out boots of the type usually employed in connection with low-pressure or balloon tires, it is essential, 85 because of the continued and extraordinary 90 flexing of the tire casing and enclosed blow-out boot, that the boot be made of relatively thin and flexible material, usually about two 95 ply cord fabrics. It is obvious that with such thin boots, the tendency of the edge fastening means to pull through, fray out or unravel the edges of the boot, is greatly increased.

An object of my invention is to provide 100 an improved reinforcement for the longitudinal edges of a blow-out boot, by means of which the staples, eyelets or other fastening means may be positioned immediately adjacent the edges of the fabric of the boot, and in which the edges are materially reinforced or strengthened to prevent said fastening means from pulling through, unraveling, or fraying out the edges of the boot 105 when the boot is subjected to expansive pressure within the tire casing.

A further object of my invention is to provide an edge reinforcement for blow-out boots, consisting of a strip or section of relatively tough and inelastic material extending along the longitudinal edges of the boot and secured to the boot by stitching or other suitable means at a point remote from the edge thereof, the staples, eyelets, or other fastening means passing through this reinforcing strip and through the edge of the material of the boot, to form a means of securing the boot in position about the inner tube.

In the accompanying drawings, forming a part of this specification and in which like numerals are employed to designate like parts throughout the several views:

Fig. 1 is a plan view of one form of blow-out boot showing my improved edge-reinforcing means applied thereto, and

Fig. 2 is a fragmental perspective view through one edge of the boot, showing, on an enlarged scale, the relative position of the reinforcing means with respect to the body of the boot.

Referring to the drawings, wherein for the purpose of illustration is shown a preferred embodiment of my invention, the numeral 1 designates a blow-out boot, constituted of a plurality of laminations of knitted or woven fabric or cord material. At opposite ends of the fabric, are preferably secured end flaps 2 of rubber or other suitable material, and at or near one longitudinal edge or side of the boot is secured a protecting strip 3 of rubber or the like which is adapted, when the boot is secured about an inner tube, to be interposed between the said tube and the fastening means to prevent any possibility of the tube being pinched or rubbed at this point. Attached to the outer side of the lamination of fabric composing the boot, is a sheet of rubber 4, attached to the boot at or near its opposite edges. All of the above construction of boot is old and well known in the prior art and forms no part of my present invention, this form of boot being disclosed in my patent, Reissue, 15,174, of August 21, 1921, and merely being selected by me to illustrate my improved reinforcing means to be presently described.

My invention consists in the reinforcing or strengthening strip 5, made of closely knit or woven fabric, leather, or other relatively tough and inelastic material, secured at opposite sides of the boot with its outer edge flush with the edge of the boot. This reinforcing strip 5 is made relatively wide and is preferably attached to the upper surface of the boot by means of stitching 6, which stitching passes through the strip near its inner edge and in a line or lines remote from the edge of the boot 1. It is to be noted that at one side of the boot the stitching 6 is em-

ployed to secure or attach the inner protecting strip 3, one edge of the rubber sheet 4 and the reinforcing strip 5, to the fabric body of the boot, and at the opposite side of the boot, to attach the other edge of the rubber sheet 4, and the second reinforcing strip 5.

Secured to each of the opposite longitudinal edges of the boot are a row of staples or loops 7 arranged to extend beyond the longitudinal edges of the boot, and provided at their inner ends with penetrating prongs which are driven into the edge of the boot. It is to be noted particularly that the upper prongs of these staples or loops extend through the reinforcing strips 5, the rubber sheet 4, and into the fabric 1 of the boot. These loops or staples are arranged in staggered relation and, when the edges are brought together about the inner tube these coacting loops fit together to form a closed passage for a suitable locking thong or strip (not shown) by means of which the boot is maintained in position about the inner tube. While I have elected to illustrate my invention as used in connection with the staple or loop fastening means, it is to be understood that eyelets or other forms of fastening means may be employed, it being only essential that such fastening means pass through the reinforcing strips 5 and through the fabric body of the boot.

It will thus be seen that I have provided a novel and useful means for reinforcing the edges of a blow-out boot to prevent the staples, eyelets or other fastening means from pulling through, unravelling, or fraying out the edge of the fabric of which the boot is constructed. The reinforcement is usually made of double-ply, closely woven fabric, and is especially adapted for use in connection with boots made of cord material. The stitching being positioned at an appreciable distance from the edge of the boot, takes the pull or strain off of the immediate marginal edge of the boot and thus prevents the strain due to the inflation of the tube, from pulling the fastening means free from the boot. Were it not for this tough and inelastic edge reinforcing strip the strength of the boot, whether made of fabric or cord material, would depend entirely upon the strength of the edge of the fabric and the ability of such edge fabric to withstand the pull on the fastening means. When it is desired to employ the usual cord fabric for making the boot, such a reinforcement is not only desirable, but is almost a necessity, because of the diagonal positioning of the cords and the location of the staples, eyelets, or other fastening means at the extreme edge of the fabric. By my construction, I combine what little strength there is in the cord fabric, reinforce or strengthen it with the closely woven fabric, leather or other strip, and sew

the strip and boot together, putting the reinforcing strip on the outside, where it gets the heaviest or greatest strain, and pass the staples, eyelets or other fastening means into 5 and through the boot fabric and reinforcing strip to give such fastening means a firm and substantial hold or foundation.

It is to be understood that the form of my invention herein shown and described is 10 to be taken as a preferred example of the same and that various changes in the construction, size and arrangement of parts may be resorted to without departing from the spirit of the invention or the scope of 15 the subjoined claims.

Having thus described my invention, what I claim as new and desire to secure by Letters Patent is:—

1. A blow-out boot comprising a body portion, reinforcing and strengthening strips secured at opposite sides of the body portion, and fastening means passing through said reinforcing and strengthening strips and through the body portion of the boot.

25 2. A blow-out boot comprising a body portion, a reinforcing and strengthening strip positioned along the edge of the body portion with its outer edge flush with the edge of the said body portion, means for attaching said reinforcing and strengthening strip to said body portion at a point remote from the edge of the body portion, and fastening means passing through said reinforcing and strengthening strip and through the 30 body portion of the boot.

35 3. A blow-out boot comprising a body

portion of cord fabric, a reinforcing and strengthening strip positioned at the edge of said cord fabric, means for attaching the inner edge of said reinforcing and strengthening strip to said body portion at a point remote from the edge of the body portion, and fastening means passing through the reinforcing and strengthening strip near its outer edge and through the cord fabric body 40 portion near the outer edge thereof.

4. A blow-out boot comprising a body portion of cord fabric, a reinforcing and strengthening strip superimposed along the edge of the body portion with its outer edge 50 flush with the edge of said body portion, stitching passing through the reinforcing and strengthening strip and through the body portion at a point remote from the edge of the body portion for attaching the 55 strip and body portion together, and fastening means passing through said reinforcing and strengthening strip and through the body portion near the outer edge of each.

5. A blow-out boot comprising a body 60 portion of cord fabric, a reinforcing and strengthening strip secured at opposite sides of the body portion near the edge thereof, said strip being made of tough inelastic material, and fastening means passing through 65 said reinforcing and strengthening strip and through the body portion near the outer edge of each.

In testimony whereof I hereunto affix my signature.

JOHN A. BARNES.
